Specification of Letters Patent.

Patented Aug. 6, 1918.

Application filed February 19, 1918. Serial No. 218,082.

To all whom it may concern:

Be it known that I, PINKNEY P. FRAZER, a citizen of the United States of America, residing at St. Louis, in the State of Missouri, have invented certain new and useful Improvements in Bearings, of which the following is a specification.

This invention relates to bearings and has for its object the provision of simple and effective means whereby a bearing may be quickly tightened when it becomes necessary to compensate for the wear of the Babbitt metal or other like substance with which bearings are commonly lined.

15 In the accompanying drawing, where like numerals refer to like parts throughout the several views, Figure 1 is a top plan view of the complete improved bearing shown in connection with an emery wheel or other 20 like tool the shaft of which projects therethrough; Fig. 2 a top plan view with the upper brass of the bearing removed and inverted, so as to expose the interior arrangement; Fig. 3 a vertical longitudinal section 25 taken along line 3—3 of Fig. 1; and Fig. 4 an end elevation taken along line 4—4 of Fig. 1.

In carrying this invention into practice I provide inclined slots 1 and 2 in the lower 30 brass 3 of a conventional type of bearing and insert therein wedge-shaped keys 4 and 5 which are best shown in Fig. 3, the upper edge of each key being formed with a lug 6 and these lugs projecting through 35 openings 7 and 8 provided in the flanges 9 and 10 of the upper brass 11.

Assuming that the brasses have been 40 newly lined and the parts are being assembled, it will be appreciated that keys 4 and 5 are driven inward to substantially their full length as shown in Fig. 3 so that when the upper brass 11 is positioned its flanges 9 and 10 will rest upon the upper edge of said keys with the result that its 45 bushing (*i. e.* its Babbitt lining) is separated from the bushing of the lower brass 3 to the extent of approximately a quarter-inch as best shown in Fig. 4.

Thereafter, when the lining has been worn by the friction of shaft 12 and it becomes 50 necessary to alter the original adjustment so as to tighten the bearing, set-screws 13 are loosened and keys 4 and 5 driven outwardly to a slight extent by tapping upon lugs 6 so as to permit the top brass to descend to 55 an extent sufficient to compensate for the wear, whereupon said screws are turned inwardly to retain said keys in their new location and the brasses are secured together by tightening nuts 14 upon bolts 15 which 60 project from the base of standard 16.

From the foregoing it will be clear that the application of this invention is not limited to any particular tool or class of machines and that, in addition to other uses, 65 it will be found of distinct value in line shafting where it is of prime importance to effect necessary repairs as rapidly as possible, and the right is reserved of making such changes in the form and proportion 70 of the several elements as experience may determine without departing from the spirit of the invention or the scope of the following claims.

What I claim as new and desire to secure 75 by Letters-Patent is:—

1. A bearing comprising a lower brass having inclined slots formed therein, keys disposed in said slots substantially corresponding to the formation thereof, a detachable brass disposed over said keys and supported thereby, and means for connecting said brasses.

2. A bearing comprising a lower brass having inclined slots formed therein, keys 85 disposed in said slots substantially corresponding to the formation thereof, lugs projecting from the upper edge of said keys, a detachable brass disposed over said keys and supported thereby having openings in 90 register with said lugs, and means for connecting said brasses.

PINKNEY P. FRAZER.
